GAS COMPRESSOR AND VALVE THEREFOR

Kenneth K. Cooper, Fort Wayne, Ind., assignor to General Electric Company, a corporation of New York

Application May 14, 1952, Serial No. 287,747

1 Claim. (Cl. 137—516.15)

This invention relates to gas compressors and particularly to compressors of the reciprocating type and valves therefor.

When reciprocating compressors are operating at high speeds, difficulty is frequently encountered because of inefficient valve operation and valve breakage and resulting shutdown periods. Some of the most efficient valves are those comprising flexible valves or reeds, and various arrangements have been proposed to minimize breakage of these valves and to secure efficient operation with minimum noise and wear. It is an object of the present invention to provide an improved compressor construction including an arrangement of valves such that noise and breakage are reduced to a minimum.

It is another object of this invention to provide an improved valve of the flexible reed type particularly suitable for reciprocating compressors.

Further objects and advantages of the invention will become apparent as the following description proceeds, and the features of novelty which characterize the invention will be pointed out with particularity in the claims annexed to and forming a part of this specification.

In carrying out the objects of this invention, a compressor including a cylinder block and a compressor head having exhaust passages therein and a valve plate between the block and head is provided with annular valve seats and thin spring metal valves in the form of flat rings engaging the annular valve seats and controlling the passage of gas through the intake and discharge ports of the compressor. The flexible ring valves are loosely mounted adjacent the valve plate, and their outer peripheries are restrained from any substantial bodily movement away from the plate, while a portion adjacent the inner periphery which acts as the port closing member is free to flex away from the plate in a conical form. To limit the flexing movement of the valve, conical backing members are provided which extend around the entire circumference of the valve area. The discharge valve is formed by providing a circular opening in the valve plate in which is mounted a disk spaced from the edge of the opening about its periphery and cooperating to provide an annular valve port. The disk is secured to the compressor head. The intake valve also comprises a continuous annular port and is connected with the intake of the compressor through a series of radial passages extending through the valve plate to its periphery, and the compressor head and block are provided with lateral flanges cooperating to form an annular muffling chamber about the valve plate, this chamber being closed by a perforated baffle.

For a better understanding of the invention, reference may be had to the accompanying drawing in which Fig. 1 is a sectional elevation view of a reciprocating compressor embodying the invention, and Figs. 2 and 3 are plan views illustrating the preferred forms of discharge and intake valves of the compressor of Fig. 1.

Referring now to the drawing, the compressor as illustrated comprises a cylinder block 10 and a cylinder head

2

11 clamped together by suitable bolts or other devices (not shown) against a valve plate 12 which fits within circular seats 13 and 14 in the block and head respectively. The valve plate is spaced from the block and head by washers or annular spacing gaskets 15 and 16 respectively. The block 10 is provided with a cylinder having a liner 17 brazed or otherwise suitably secured within a cylinder bore 18 of the block, and a piston 19 is mounted for reciprocation within the cylinder, it being connected through a connecting rod 20 in the usual manner to a motor driven crank (not shown). The remainder of the compressor, including the case and driving mechanism, is not shown as it is not necessary to an understanding of the present invention. The connecting rod 20 drives the piston in the usual manner through a wrist pin 21. The valve plate 12 is provided with a circular opening 22 concentric with the cylinder 17 and having its lower end of the same diameter as the bore of the cylinder, its upper end being shown tapered slightly inwardly. An annular exhaust port 24 is formed within the opening 22 by a circular disk 25 the outer periphery of which is spaced from the plate 12, the disk being held rigidly in position by a threaded connecting member or bolt 26 fitted in a downwardly extending cup-shaped member 27 forming a part of the compressor head 11, and secured by nut 28.

It will be noted that the top of the piston 19 is shaped to conform to the space about the disk 25 so that the piston fills this space when in its uppermost position; this assures minimum clearance volume and efficient operation.

The plate 12 is also provided with an annular intake port 29 opening into the cylinder by way of a conical recess 30 at the side of the cylinder and formed by chamfering the cylinder block about the upper end of the cylinder. The port 29 communicates with the outside of the compressor through a plurality of radial passages 31 opening about the periphery of the plate into an annular recess 32 of generally triangular cross section. The recess 32 is formed by laterally extending flanges 33 and 34 on the cylinder block and head respectively, these flanges having their facing surfaces diverging outwardly and terminating in shouldered recesses 35 and 36 respectively in which is mounted a band 37 for enclosing the recess 32. The band 37 is provided with a plurality of perforations 38 and the recess 32 therefore acts as a muffler or muffle box for the intake valves and minimizes the sound transmitted from the valves.

The discharge and intake ports 22 and 29 are closed by flexible ring valves 40 and 41 respectively. These valves are constructed of spring material of thickness 50 slightly less than that of the spacing members 15 and 16 so that the valves are free rather than clamped but are restrained against any substantial bodily movement away from the valve plate at their outer peripheries. The flexing movement of the intake valve 41 away from the port 29 is limited by the sloped wall of the cylinder block, which is shaped in conical form to provide a backing member 42, and the valve 41 is therefore free to flex conically between its position seated against the port 29 and a position against the backing member 42. A backing member 60 43 is provided for the discharge valve 40, and the discharge valve flexes conically in the same manner as the intake valve, its inner rim portion moving between its position against the valve plate 12 and a position against the backing member 43.

Although the valves may be made as plain rings, in the preferred form of the invention as illustrated both the discharge valve 40 and the intake valve 41 have their outer peripheries scalloped as indicated in Figs. 2 and 3 respectively. This scalloping of the edges is desirable in order to reduce stiffness of the valve and the stress in the valve for a given lift away from the valve seat. Furthermore, in

the case of the discharge valve the scallops as indicated at 45 provide openings through which the gas may escape from the port 24 on both sides of the central portion of the valve, and the valve backing member 43 is provided with openings 46 registering with the scallops to afford passage of the compressed gas into the discharge chamber within the head 11. By providing this additional area for the discharge of gas it is possible to employ a lower lift of the valve and therefore a lower stress in the valve, thereby increasing the effective life of the valve.

During operation it has been found that compressors provided with valves of this type are less noisy than compressors with conventional flexible or reed type valves and that the valves are longer lived than circular or disk flexible valves wherein the outer periphery moves away from the valve plate.

While the invention has been illustrated in connection with a specific type of compressor, other applications will readily be apparent to those skilled in the art. It is not, therefore, desired that the invention be limited to the specific details illustrated, and it is intended by the appended claim to cover all modifications which fall within the spirit and scope of the invention.

What I claim as new and desire to secure by Letters Patent of the United States is:

A discharge valve assembly for use in compressors and the like comprising a valve member having a flat face, said valve member having porting means providing an annular porting zone in said flat face of said member for the passage of gas through said valve member, a valve for controlling said porting means comprising a thin flat ring of flexible metal engaging said flat face of said member and

mounted concentrically with said porting zone and having a continuous portion near its inner periphery covering said porting zone and a scalloped outer circumferential edge portion, and means providing a conical backing member 5 for said valve ring extending from the outer periphery of said ring toward the center thereof and axially away from said flat face, said backing member having openings therein registering with the scallops in the outer edge portion of said valve ring and affording passages for discharge gas, 10 said backing member at its portion nearest the outer rim of said ring being spaced from said valve seat a distance slightly greater than the thickness of said valve ring whereby the outer scalloped edge portion of said ring is restrained against movement away from said face but is 15 freely mounted to afford flexing of its inner portions about its outer rim and conically toward said backing member.
